CLAIM

The ornamental design for a handbag insert, as shown and described.

DESCRIPTION

FIG. 1 is a front view of a handbag insert showing my new design;

FIG. 2 is an end view thereof;

FIG. 3 is an opposite end view thereof;

FIG. 4 is a back view thereof;

FIG. 5 is a top view thereof;

FIG. 6 is a bottom view thereof;

FIG. 7 is a top view of the handbag insert after being opened; and,

FIG. 8 is a perspective view of the handbag insert.

In the drawings, the broken lines depict unclaimed subject matter only and form no part of the claimed design.
